(57) **CLAIM**

The ornamental design for a shoe with logo, as shown and described.

DESCRIPTION

FIG. 1 is a side perspective view of a shoe with logo, according to one embodiment of this design;

FIG. 2 is a front view of a shoe with logo, as shown in FIG.

1;

FIG. 3 is a rear view of a shoe with logo, as shown in FIG.

1;

FIG. 4 is a top view of a shoe with logo, as shown in FIG.

1;

FIG. 5 is a bottom view of a shoe with logo, as shown in

FIG. 1;

FIG. 6 is a side view of a shoe with logo, as shown in FIG.

1; and

FIG. 7 is a side view, opposite the side view shown in FIG.

6, of a shoe with logo, as shown in FIG. 1;

FIG. 8 is a side perspective view of a shoe with logo,

showing another embodiment of the design;

FIG. 9 is a front view of a shoe with logo, as shown in FIG.

8;

FIG. 10 is a rear view of a shoe with logo, as shown in FIG.

8;

FIG. 11 is a top view of a shoe with logo, as shown in FIG.

8;

FIG. 12 is a bottom view of a shoe with logo, as shown in

FIG. 8;

FIG. 13 is a side view of a shoe with logo, as shown in FIG.

8; and,

FIG. 14 is a side view, opposite the side view shown in FIG.

13, of a shoe with logo, as shown in FIG. 8.

The dashed lines are included for the purpose of showing portions of the shoe with logo that form no part of the claimed design.
